(57) CLAIM

The ornamental design for a bikini with a set of interchangeable ornamental clasps, as shown and described.

DESCRIPTION

FIG. 1 is a front view of a bikini with a set of interchangeable ornamental clasps.

FIG. 2 is a side view of the bikini as it would appear when being worn, with the interchangeable ornamental clasp in the center of the bikini top shown in a side view and the interchangeable clasp on the bikini bottom shown in a perspective view; and,

FIG. 3 is a perspective view of a bikini with the set of interchangeable ornamental clasps.

The bikini top has an interchangeable ornamental clasp where the right and left portions meet. Additionally, the bikini bottom has two interchangeable ornamental clasps one positioned on each side of the front loin cover portion of the bikini.

The broken lines depicting a bikini illustrate portions of the bikini with interchangeable clasps that form no part of the claimed design. The broken lines depicting a human figure illustrate environmental subject matter that forms no part of the claimed design.
